UNITED STATES PATENT OFFICE.

FRANK M. MAHAN, OF CHICAGO, ILLINOIS.

AERIAL NAVIGATOR.

No. 861,133.

Specification of Letters Patent.

Patented July 23, 1907.

Application filed August 21, 1905. Serial No. 275,013.

To all whom it may concern:

Be it known that I, FRANK M. MAHAN, a citizen of the United States, residing in Chicago, in the county of Cook and State of Illinois, have invented a new and 5 useful Improvement in Aerial Navigators, of which the following is a specification.

This invention relates to an improvement in aerial navigators. In it I employ a buoyant vessel adapted to support a large proportion of the weight of the apparatus and its load. This proportion I estimate should be about 95 per cent, and my purpose in this feature 10 is to prevent any quick falling of the apparatus consequent upon the disarrangement or breaking of the propelling apparatus, the buoyant vessel insuring a slow 15 and gradual descent.

My invention also employs as the propelling means, a pair of wings joined to the central portion of the buoyant vessel and vibrated by a suitable motor carried in the cage of the navigator. These wings are preferably 20 shaped as near as may be like the wings of a bird, and they are given lifting and propelling movements resembling those of the bird's wing. They also resemble a bird's wings in that they are adapted to permit the passage of air freely through them when the motion 25 is upward, and to prevent such passage of air when the navigator is soaring or moving down. This feature of the invention consists in providing the wings with air openings through them, guarded by valves which automatically open when the movement is upward and 30 close when it is horizontal or downward. The buoyant vessel forming the body of the navigator is given its greatest diameter at its longitudinal center, and diminishes from the center toward each end, and the basket carrying the motor and operator is supported 35 immediately below the center of the body, the construction being such that all the lines of the support converge at the center of the basket, where the motor is located, thus establishing an equilibrium between the two ends of the navigator. This equilibrium is 40 maintained at all times, notwithstanding the changes in the position of the operator. The body is also broader at the top than at the bottom, so that its tendency to rock sidewise is reduced to a minimum. Said body is further provided at its forward end with a guiding device which may be turned in any direction desired so as to direct the navigator upward, downward or laterally. It is also provided with a rudder at the rear end adapted to assist in guiding it.

These and other features of the invention are fully 45 set forth in the description given below, and illustrated in the accompanying drawing.

In said drawing Figure 1 is a side elevation of the invention. Fig. 2 is a transverse section. Fig. 3 illustrates one of the wings detached. Fig. 4 is a section on line 4—4 of Fig. 3. Fig. 5 a partial section of the wings showing one of its air valves. Fig. 6 a detail view of

the forward guiding device. Fig. 7 is a vertical section of the rudder. Fig. 8 is a section on line 8—8 of Fig. 7, and Fig. 9 is a detail of the rudder controlling mechanism.

60

In said drawing 10 represents the buoyant vessel which forms the body of the navigator. It is a closed gas holding vessel, preferably of the shape shown, that is of a large diameter at the vertical center and tapered toward each end, and also larger at the top than at the bottom. It is formed of any suitable material adapted to hold the gas, and is provided with distending ribs 11 by which it is enabled to retain its shape, notwithstanding the atmospheric pressure upon it when in motion, and, as already stated, it is charged with such an amount 70 of gas as will enable it to sustain about 95 per cent of the total weight of the apparatus and its load, thus overcoming the greater portion of the gravity so that the wings are called upon to supply only a slight amount of lifting power to enable the vessel to float. 75 The cage or basket 12 is supported from the center of the body 10 by strips 13, of which there are two at each side. In the basket is a motor 14 driving the shaft 15, carrying at its ends sprocket wheels 16, and actuating the chain 17 running over sprockets 18, on stud shafts 80 19 secured to the side of the body. The crank wheels 18 are connected by pitman 20 to the base pieces 21 of the wings. These base pieces are attached to the body by pivots 22 having bearings 23 at each end, the bearings being secured to the body near its top. By this 85 mechanism I am enabled to convert the rotary motion of the motor and give the wings the lifting and propelling movements desired; but it will be understood that I do not wish to be limited to this type of mechanism, as any other suitable transmitting mechanism may be 90 employed in its stead.

The wings consist of the bases 21, and of a main portion attached thereto. This main portion is given considerable area and is made as light as possible. In the construction which I prefer it consists of hickory 95 ribs 24, and a cover, preferably upon both sides of such ribs, of rubber or equivalent cloth 25. The ribs are all hinged to the bases 21, as shown at 26, and they are employed in such number as may be desirable. I also secure to the cloth 25, flat strips 27 of aluminium 100 or other suitable material, and in such strips and also in the cloth to which the strips are applied, are openings 28, and preferably at the under side of the aluminium strip, I attach flat or check valves 29 adapted to close said openings when the air is not moving 105 through them. The strips 27 are preferably secured to the cloth at the top of the wings as illustrated, and the cloth at the bottom is provided with openings 30 registering with the openings 28. The wings are also provided with distending means consisting of the 110 toggles 31 and 32 and their connecting strip 33. When the toggles are extended, as in Fig. 3, the wing is fully

distended, and it may be collapsed by forcing the strip 33 toward the base 21 so as to shorten the toggles. The outer ends of the toggles are secured to the outer ribs 24, as will be understood, and a locking button is shown at 34 adapted to hold the distending devices in their open position.

At the forward end the navigator is provided with a guiding device 35, preferably cone-shaped, as illustrated. It is supported on the end of a bar 36, pivoted at 37 in a slotted rocking bar 38 supported in the arms 39 projecting forwardly from the ring 40 at the forward end of the body 10. The bar 36 is connected by a cord 41 to the basket and the cord passes over the sheave 42 so that by pulling upon said cord, the guide 35 may be raised, the slotted bar 38 then rocking on its pivots. To lower the guiding device, another cord 43 attached to its under side and extending to the basket is operated. Another cord 44 is attached to the inner end of the bar 36, and by pulling upon one end of it the guide 35 is moved laterally in one direction and by pulling upon the other end of it, the guide is turned laterally in the opposite direction. A sleeve 60, see Fig. 6, made of rubber or other flexible material, covers the joints and keeps out wind and rain.

25 The rudder is shown at 45 and a transverse pin 46 moving in the circular slot 47 in the cone-shaped thimble 48 forming the rear end of the body 10 supports the rudder. A rod 49 extends from the basket and is joined to the rudder by a universal joint which permits the turning of the rudder from the vertical to the horizontal position, or to any intermediate position, and the rudder may also be deflected to any angle desired relative to the axial line of the body, rocking in so doing, upon the supporting pin 46. The rod 49 may be rocked by the lever 50, and adjusted longitudinally by the lever 51.

The operation of the navigator is as follows: Supposing the body to be charged with sufficient gas, so that its buoyancy equals 95 per cent of the weight of the apparatus and its load, and that the wings are distended and motion given to them, the navigator will begin to move, the wings supplying any deficiency in the buoyancy of the body, necessary to overcome the gravity, and if the guiding devices are adjusted so as

to cause the upward movement, the navigator will rise to any height desired. During the upward movements of the wings, the valves open so that the air passes down freely through them and offers no resistance to the upward movement, and they close during the downward movement thereof and whenever 50 the upward movement ceases. When the vessel has reached the desired height, the guiding devices may be adjusted for horizontal movement, and the wing valves then close because the downward currents of air through them will have ceased and the wings' 55 efficiency as supporting means is thereby increased because they are adapted to hold the air beneath them. It will be noticed that the wings are somewhat concave in cross-section; and when the valves close, as stated, they are adapted to retain a considerable body of air 60 and the increased buoyancy due to this continues so long as the navigator moves horizontally or downwardly.

While the construction I have shown is the best now known to me, it will be understood that I do not wish 65 to be limited to mere details of construction nor to the materials described for the various parts.

I claim:

1. An aerial navigator having a buoyant body, a car suspended therefrom, propelling and lifting wings hinged to the sides of the body, a motor in the car having a cross shaft extending under the body, and connections between the ends of the shaft and the wings, to operate the latter.
2. An aerial navigator having a buoyant body, a car suspended therefrom, wings hinged to the sides of the body, 75 stud shafts secured to the sides of the body and having cranks connected to the wings, a motor carried by the car and having a cross shaft under the said body, and gearing between the cross shaft and the stud shafts.
3. In an aerial navigator, a wing having ribs, covers on 80 both the upper and lower sides of the ribs, said covers having openings therethrough, and valves for the openings in the upper cover, said valves being located in the space between the covers.
4. In an aerial navigator, a wing having ribs, a flexible 85 cover over the ribs, and toggles connected to the outer ribs and extending across the wings to expand or contract the same.

FRANK M. MAHAN.
